UNITED STATES PATENT OFFICE.

ALEXANDER A. WELSH, OF ALLEGHENY, PENNSYLVANIA, ASSIGNOR, BY DIRECT AND MESNE ASSIGNMENTS, TO THE CRAWLEY SCENIC AND PLEASURE RAILWAY COMPANY, OF CINCINNATI, OHIO.

ELEVATED SINGLE-RAIL RAILWAY.

SPECIFICATION forming part of Letters Patent No. 663,525, dated December 11, 1900.

Application filed August 20, 1900. Serial No. 27,499. (No model.)

To all whom it may concern:

Be it known that I, ALEXANDER A. WELSH, a citizen of the United States, residing at Allegheny, in the county of Allegheny and State 5 of Pennsylvania, have invented new and useful Improvements in Elevated Single-Rail Railways, of which the following is a specification.

My invention relates to elevated single-rail 10 railways employing guard-rails, its object being to provide an inexpensive and safe structure and running-gear adapted thereto.

The invention is particularly useful in pleasure-railways, where high speeds are 15 customary.

To this end my invention consists, first, in a track-support designed to carry both bearing-rail and guard-rails in a safe and secure manner and in such relations as admit of a 20 form and construction of running-gear particularly adapted thereto and to secure entire safety at high speeds and also convenient for due inspection and maintenance, and, second, in a construction and arrangement of the running-gear adapted to the rail structure, whereby 25 the maintenance of the equilibrium of the car is assured under all circumstances and derailment absolutely prevented.

My invention is illustrated in the accompanying drawings, in which—

Figure 1 is an elevation of one of the members of the trestle, showing the manner of supporting the main bearing-rail and guard-rails; also, an end elevation of a car in position upon the bearing-rail and in due relation with the guard-rails. Fig. 2 is a similar elevation of structure designed to carry two of such single-rail railways each independent.

Referring now to the drawings, A A design-40 ate the two outer struts or braces of a trestle seated upon a base B, and C a central vertical prop the top of which is secured to a cross-brace D, connecting the outer struts. To the tops of the center props C is secured 45 a stringer D', upon which is carried the bearing-rail R. The inclined side struts A A are carried upward to a suitable height above the level of the main track, and at the inner sides of the same are secured stringers a a at each 50 side of the main bearing-rail R, respectively.

Guard-rails r r are secured to the under side of the stringers a a.

The relative positions of the parts described are indicated in Fig. 1, wherein is shown a double-flanged central bearing-wheel 55 E, running loosely upon fixed axle e, at the outer terminals of which are carried guard-wheels F, flanged at the inner sides. The relations of the parts are such that jumping of the central bearing-wheel E from its track R 60 is prevented by the upward contact of the guard-wheels F against the guard-rails r, seated upon the stringers a.

The car-body G rests upon stringers g g, to which are secured boxes h, in which the axle-bar e is rigidly fastened and in which also may be placed friction rollers or balls (not shown) in the usual manner to minimize the rotative friction of the wheels E and F. It will be readily seen that the oscillations of the 70 car-body relate to a center which is the point of rolling contact of the wheel E with the track R and that such oscillations involve the sweep of the outer ends of the axle-bar e in upward and correspondingly downward 75 arcs. While in rapid motion forward, the tendency is to maintain a horizontal equilibrium of the car-body, in which position the guard-wheels F are maintained just below the plane of contact with the guard-rails r. Any 80 oscillation, however, brings one of the guard-wheels into contact with its guard-rail, and as the provision for lost motion is very small the oscillation is limited to very minute arcs. The equilibrium is therefore practically main- 85 tained at all times by the guard-wheels, besides absolutely preventing the bearing-wheel E lifting sufficiently from its track-rail R to disengage its flanges. Derailment is therefore absolutely prevented.

As the structure is designed for safety at high speeds, it will be understood that the surging effect of momentum increases the force of oscillation, &c. To meet these conditions is the object of the construction shown, 95 in which the guard-rail stringers are mounted as an integral part of the structure upon the upward extension of the struts A. It will be seen that the arcs of oscillation at the point of contact of the guard wheels and rails r are 100

substantially parallel with the longitudinal axes of the struts A themselves, and the lifting force upon the struts at such points is resisted by the weight of the car and of the 5 entire structure. There is thus constituted a simple, cheap, and exceedingly-effective structure, tending to make high speed absolutely safe so long as the parts themselves are maintained in a reasonable state of repair.

10 The principle of construction may be carried out in a structure for a double railway where tracks are parallel, as indicated in Fig. 2. In this case the outer struts A A are spread apart, and the central braces C are 15 carried upward beyond the cross-brace D sufficiently to carry at opposite sides stringers a' a', corresponding with the stringers a, before described. Stringers D' for the main rail R are carried on the cross-brace D, while 20 guard-rails r are placed at the under side of the side stringers a' a'. Additional braces x y may be inserted to strengthen the structure, if needed.

It is not broadly new to provide single-rail 25 railways with guard-rails for the operation of guard-wheels bearing against the same; but so far as I am aware the guard-rails have never before been arranged in the relation to the track here shown so that the guard- 30 wheels can be carried on the same axle with the bearing-wheel as part of the running-gear in a compact construction, so that the whole structure is simple, efficient, and "practical" in a high degree and easily so maintained.

35 I claim as my invention and desire to secure by Letters Patent of the United States—

1. In a single-rail railway system, the combination of a fixed axle; a double-flanged bearing-wheel centrally pivoted thereon; 40 guard-wheels of lesser diameter journaled at the extremities thereof; a main central rail carrying the bearing-wheels; and guard-rails carried at the sides of and above the main rail and guard-wheels and approximately in 45 the contact-path of the latter.

2. In an elevated railway system, the combination of a supporting structure, including oppositely-inclined struts and cross-braces uniting the struts below their tops; and 50 means for carrying the bearing-rail centrally between the struts above the cross-braces and guard-rails carried at the inner sides of the struts above the main bearing-rail, adapted

for the operation of a car or truck having one or more axles provided with double-flanged 55 bearing-wheels bearing upon the central rail and guard-wheels of lesser diameter journaled at the extremities of the axle beneath and in approximate contact with the guard-rails.

3. The elevated "single-rail-railway" structure embodying oppositely-inclined struts, cross-braces uniting the same below their tops, central vertical props rising to the cross-braces, a stringer for the support of the 65 main bearing-rail carried on the tops of the central props and the cross-braces, and two side stringers for the support of the guard-rails and carried at the inner sides of the inclined side struts above the cross-braces, substantially as set forth.

4. In a single-rail railway, the combination of a supporting structure including oppositely-inclined struts, means connecting them below their tops, and vertical props, a main 75 rail, a double-flanged wheel adapted to run thereon, an axle or axle-bar extending axially at both sides of said wheel, single-flanged guard-wheels at the extremities of said axle or axle-bar, and guard-rails at both 80 sides of said central track, fixed to the supporting structure above the plane of the main rail and arranged just above the normal plane of rolling contact of said guard-wheels, substantially as set forth.

5. In an elevated railway, the combination of a supporting structure including oppositely-inclined struts, horizontal braces connecting said struts below their tops and vertical posts between opposite struts, main and 90 guard rails, means for securing the guard-rails in position near the plane of the tops of the struts and means for securing the main rails in position just above the plane of the cross-braces, the main bearing-wheels, and 95 guard-wheels mounted on extensions of the axle thereof at opposite sides, said guard-wheels arranged below and in the contact-path of the guard-rails.

In testimony whereof I have hereunto set 100 my hand in presence of two subscribing witnesses.

ALEXANDER A. WELSH.
